United States Patent Office

Des. 180,982
Patented Sept. 10, 1957

180,982

CHAIR

Roy E. Woodward, Provo, Utah

Application June 26, 1956, Serial No. 42,052

Term of patent 14 years

(Cl. D15—11)

Fig. 1

Fig. 2

Fig. 3

Fig. 4

Figure 1 is a perspective view of a chair, showing my new design;

Figure 2 is a rear elevational view of the same;
Figure 3 is a top plan view of the same; and
Figure 4 is a side elevational view thereof.

I claim:

The ornamental design for a chair, as shown.
